Primary Examiner — T Chase Nelson*Assistant Examiner* — Kelly L Gross(74) *Attorney, Agent, or Firm* — Maschoff Brennan(57) **CLAIM**

The ornamental design for a matrix ring, as shown and described.

DESCRIPTION

FIG. 1 is a first perspective view of a matrix ring showing the new design;

FIG. 2 is a second perspective view of the matrix ring;

FIG. 3 is a front view of the matrix ring;

FIG. 4 is a back view of the matrix ring;

FIG. 5 is a right side view of the matrix ring;

FIG. 6 is a left side view of the matrix ring;

FIG. 7 is a top view of the matrix ring; and,

FIG. 8 is a bottom view of the matrix ring.

The broken lines shown in the figures are for the purpose of illustrating portions of the matrix ring that form no part of the claimed design.
